The ornamental design for a hose reel as shown and described.

DESCRIPTION

FIG. 1 is a front perspective view of a hose reel, showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The evenly-spaced broken lines shown only in FIGS. 1-3, 5 and 8 are for purposes of illustrating portions of the hose reel that form no part of the claimed design. The additional evenly-spaced broken lines shown in FIGS. 1-7 are for purposes of illustrating environmental subject matter only and form no part thereof. The dash-dot-dot broken lines
